(57) **CLAIM**

The ornamental design for an aircraft aft position and anti-collision light, as shown and described.

DESCRIPTION

FIG. 1 is an upper perspective view of the right front of the aircraft aft position and anti-collision light.

FIG. 2 is a right side perspective view of the aircraft aft position and anti-collision light.

FIG. 3 is a right side view of the aircraft aft position and anti-collision light. The left side view is not shown because it is mirror image of the right side view.

FIG. 4 is a front view of the aircraft aft position and anti-collision light; and,

FIG. 5 is a bottom view of the aircraft aft position and anti-collision light. The top view is not shown because it is a mirror image of the bottom view.

The rear view of the aircraft aft position and anti-collision light is not shown because it has no ornamental content.

The aircraft aft position and anti-collision light is characterized by a lens and a base.
